UNITED STATES PATENT OFFICE.

CHARLES T. GROSJEAN, OF NEW YORK, N. Y., ASSIGNOR TO TIFFANY & CO., OF SAME PLACE.

DESIGN FOR A SPOON-HANDLE.

SPECIFICATION forming part of Design No. 16,216, dated September 1, 1885.

Application filed June 25, 1885. Term of patent 14 years.

To all whom it may concern:

Be it known that I, CHARLES T. GROSJEAN, a citizen of the United States, residing in the city, county, and State of New York, have invented a new and original Design for a Spoon-Handle, of which the following is a specification, reference being had to the accompanying drawings, forming part thereof.

The head of the handle of the spoon is of a paddle shape surrounded by a massive molding inclosing a shell-like honeysuckle ornament at the top. There is also a similar ornament where the head connects with the shank, and again at the bottom where the shank extends into the bowl. The back is the same, except there is a honeysuckle ornament at the heel extending over about one-third of the convex bowl.

In the drawings, Figure 1 is a front surface of a spoon on the handle of which is placed my design. Fig. 2 is a view of the reverse surface thereof.

a is the paddle shaped head. *b* is a mass-

ive molding surrounding the same, terminating at the top in a shell-like honeysuckle ornament, *c*. *d* is the shank. *e* is a similar honeysuckle ornament at the point where the head connects with the shank *d*. *f* is a similar honeysuckle ornament at the point where the shank connects with the bowl or tang. A 30 honeysuckle ornament, *g*, covers about one-third of the convex bowl of the spoon.

This design is also applicable to knife and fork handles.

I claim—

The design for a spoon-handle, consisting of a paddle shaped head, *a*, surrounded by the massive molding *b*, inclosing the shell-like honeysuckle ornament *c*, and the honeysuckle ornaments at points where shank *d* connects 40 with the head and the bowl, as shown and described.

CHARLES T. GROSJEAN.
